UNITED STATES PATENT OFFICE.

GEORGE W. SCOTT, OF CLEVELAND, OHIO.

CURTAIN-SUPPORT FOR AUTOMOBILES.

1,391,417.

Specification of Letters Patent. Patented Sept. 20, 1921.

Application filed February 20, 1920. Serial No. 360,087.

To all whom it may concern:

Be it known that I, GEORGE W. SCOTT, a citizen of the United States, residing at Cleveland, in the county of Cuyahoga and State of Ohio, have invented certain new and useful Improvements in Curtain-Supports for Automobiles, of which the following is a specification.

This invention relates to curtain supports for automobiles, and more particularly to supports for attaching curtains to the doors of the machine so that the curtains will open and close with the doors.

The object of the invention is to provide a support which will be simple in construction, quickly and readily applied to the door and which will embody adjustable features which will enable the parts of the support to be rigidly clamped together.

20 In the accompanying drawings:—

Figure 1 is an inside view of a portion of an automobile body and one of its doors, the door being partly broken away, showing my improved support applied thereto.

25 Fig. 2 is an end view of the door and support.

Fig. 3 is a section on the line 3—3 of Fig. 1.

Fig. 4 is a perspective view of the socket which is attached to the door.

30 Fig. 5 is a side view of the clamp and its shank, showing a portion of a hexagonal supporting rod clamped therein.

Fig. 6 is a section on the line 6—6 of Fig. 1.

35 In the drawings, 1 represents a portion of the vehicle body, 2 the frame of the door, 3 the outer metal panel of the door, 4 the inner covering of leather and 5 the metal strip which covers the top edge of the door. Se-40 cured to the inside of the frame 2 at a con-venient point removed from the front edge of the door is a metallic socket 6, the attach-ing means being preferably screws, which extend through the openings 8 in the socket

45 and serve also to secure in position a metallic strap 9 bent to form in effect a continuation of the socket. This socket receives a tapered shank 10, the upper end of which is formed with a circular opening 11 and is bifurcated

50 or split from the opening to the upper end thereof as indicated at 12, one of the bifurcated portions being threaded to receive a screw or bolt 13. A vertically-arranged polygonal rod 14, preferably of hexagonal form, has its lower end bent at right angles

horizontally in a rearward direction as indicated at 15, and thence laterally at right-angles to the bent portion 15, as indicated at 16, the lateral portion 16 being received in the opening 11 and clamped therein by the 60 bolt 13, the portion 16 of the rod being so positioned that one of the vertices thereof will coincide with the split 12 of the shank. By forming the rod of hexagonal shape, or other form with a plurality of sides, the 65 vertices formed by the sides will dig into the metal of the walls of the opening 11 and thus enable the rod to be firmly clamped to position.

The curtain which is represented by 17 is 70 secured in the usual way along its rear edge in the usual way by buttons and has its for-ward edge formed with the usual pocket to receive the vertical portion 14 of the rod.

In the commercial use of curtain supports 75 it is always necessary to furnish a right hand and left hand support, viz., a curtain sup-80 port to be used on the door on the right hand side of the automobile and one for the left hand side. In my improved construction the rod can be used for either side and it is only necessary for the constructor to bend the

85 rod 14 in a way that will adapt it for the door upon which it is intended to be used. For this reason the rods are shipped unbent 85 except as to the horizontal portion indicated at 16 and whether the rod shall be used for the right hand side door or the left hand side door determines in which direction the

90 part 14 shall be bent. Assuming that Fig. 2 shows the parts adapted for a door on the 95 left hand side of the automobile it is ap-95 parent that if the part 14 is bent in the op-posite direction, the rod will then be adapt-ed for use for a door on the right hand side. As above mentioned, the rod in cross-section 100 is of even-sided polygonal form, the rod be-ing so bent that a vertex of the polygon is in line with the split portion 12 of the shank and it is apparent that whichever way the 100 part 14 is bent the rod will always be in-105 serted so that a vertex will assume the pos-ition shown in Fig. 5. As a consequence of this when the screw is tightened the grip-110 ping force of the split portions of the shank tends to force the rod 16 downwardly and cause an effective biting of the vertex on the under side of the rod against the wall of the opening and by this arrangement there is an improved action of the parts.

Having thus described my invention, I claim:-

In a support of the character described, the combination with a hinged door and a curtain, of a curtain support consisting of a socket member secured to said door, a polygonal-shaped rod having corners, the said support and rod being interchangeable as right and left hand members for the door, 10 said rod having a part projecting laterally over the top edge of said door and a vertical part with an offset part between said first-mentioned parts, said rod being bend-

able for adapting same as a right or left hand rod, a shank projecting within said 15 socket member, an engaging member on the shank, and means for clamping said engaging member against the corners of said rod in the various positions assumed by said rod for the purpose specified. 20

In testimony whereof, I have hereunto set my hand this 16th day of February, 1920.

GEORGE W. SCOTT.
